UNITED STATES PATENT OFFICE.

ISAAC JACKSON TURNER, OF PRINCETON, NEW JERSEY.

CHIMNEY-COWL.

SPECIFICATION forming part of Letters Patent No. 402,365, dated April 30, 1889.

Application filed May 12, 1888. Serial No. 273,714. (No model.)

To all whom it may concern:

Be it known that I, ISAAC JACKSON TURNER, of Princeton, in the county of Mercer and State of New Jersey, have invented a new and Improved Chimney-Cowl, of which the following is a full, clear, and exact description.

Reference is to be had to the accompanying drawings, forming a part of this specification, in which similar letters of reference indicate 10 corresponding parts in all the figures.

Figure 1 is a sectional elevation of my new and improved cowl. Fig. 2 is a plan view of the same. Fig. 3 is a sectional elevation showing a modification. Fig. 4 is a plan view of 15 the same.

A represents the flue through which the ascending smoke and products of combustion pass from the chimney to the open air. This is, by preference, made square, and in it is secured the truncated cone or pyramid B, above which is held the cover or guard C, having side walls, c, so that the ascending smoke will be deflected downward, as indicated by arrows 1, and so, also, that any downdraft of 20 external air striking the outer surfaces of the walls c will be deflected into the space D between the cone B and the outer flange, E. This outer flange or casing E serves as a guard to prevent wind from blowing directly 25 over the top of the cone B.

In the form of cowl shown in Figs. 3 and 4 the flange reaches to a level with the top of the cover or guard C, and at the angles formed by the flange E and cone or pyramid 35 B are formed the openings d d, for the escape of the downdraft, and over these openings are hinged the doors d', which prevent the wind from blowing in, but do not impede the exhaust or escape of the downdraft.

40 In the form of cowl shown in Figs. 1 and 2 I employ an intermediate guard, F, the upper edge of which reaches to a level with the top of the cover C and lower edge reaches below the top of the flange E. To the upper 45 edge of the guard F, I hinge the doors d', which rest normally upon the upper edge of the flange E, and prevent wind from blowing down between the wall F and flange E. The downdraft that enters the guard F follows 50 the direction of the arrows 2 and leaves by

the doors d' and escapes from the cowl without in any manner impeding the draft of the chimney.

The guard F may be supported by straps or braces f f', extending, respectively, from the 55 inside of the guard to the cone B and from the outside of the guard to the casing E.

By providing a number of doors at different points of the compass, and using the inclined sides of the cone or deflector B to deflect the 60 downdraft to the proper door or doors, I obtain excellent results. The use of the open flue A and the protecting cover or cap C in connection with the doors is also important, since it affords a proper and ample means of 65 exit for the products of combustion, and yet if wind should get under the cover C it could pass across the top of the flue and be deflected downwardly on the other side of the inclined edges c of the cover.

Having thus described my invention, what I claim as new, and desire to secure by Letters Patent, is—

1. In a chimney-cowl, the combination, with a number of outwardly-swinging doors for 75 the escape of downdrafts located on the cowl at different points of the compass, of a deflector arranged within the cowl for directing the downdrafts to the doors, substantially as and for the purpose set forth.

2. In a chimney-cowl, the open flue or body A, arranged centrally therein, the cover C, the casing or flange E, and the outwardly-swinging doors for the escape of downdrafts.

3. The combination of the flue or body A, having a contracted top, the cover C, placed over and in close proximity to the flue or body A, the outer flange or casing extending around the mouth of the flue or body A, and the hinged doors d', substantially as set forth.

4. The pyramidal or contracted flue or body A, having the cover C, in combination with the flange or casing E, intermediate plate, F, and doors d', hinged to the top of the plate F, substantially as described.

ISAAC JACKSON TURNER.
